US0D1074602S

(12) **United States Design Patent** (10) **Patent No.:** **US D1,074,602 S**
(45) **Date of Patent:** **** May 13, 2025**

(54) **ELECTRICAL TERMINAL**

(71) Applicant: **Luxshare Precision Industry Company Limited**, Shenzhen (CN)

(72) Inventors: **Liang Yu**, Shenzhen (CN); **Min Fan**, Shenzhen (CN)

(73) Assignee: **LUXSHARE PRECISION INDUSTRY COMPANY LIMITED**, Shenzhen (CN)

(**) Term: **15 Years**

(21) Appl. No.: **29/881,137**

(22) Filed: **Dec. 28, 2022**

(30) **Foreign Application Priority Data**

Aug. 29, 2022 (CN) 202230567982.8

(57) **CLAIM**

The ornamental design for electrical terminal as shown and described.

DESCRIPTION

FIG. 1 is a front view of an electrical terminal showing our new and ornamental design;

FIG. 2 is a rear view thereof;

FIG. 3 is a left-side view thereof;

FIG. 4 is a right-side view thereof;

FIG. 5 is a top view thereof;

FIG. 6 is a bottom view thereof; and,

FIG. 7 is a perspective view thereof.

The broken lines in the drawings depict portions of the electrical terminal that form no part of the claimed design.

1 Claim, 3 Drawing Sheets
